UNITED STATES PATENT OFFICE.

WAYNE ZONKER, OF CORUNNA, INDIANA.

FEED-TROUGH.

SPECIFICATION forming part of Letters Patent No. 629,415, dated July 25, 1899.

Application filed March 1, 1899. Serial No. 707,291. (No model.)

To all whom it may concern:

Be it known that I, WAYNE ZONKER, a citizen of the United States, residing at Corunna, in the county of De Kalb and State of Indiana, have invented a new and useful Feed-Trough, of which the following is a specification.

The invention relates to improvements in feed-troughs.

10 The object of the present invention is to improve the construction of feed-troughs and to provide a simple, inexpensive, and efficient one designed for supplying feed to sheep and other animals and capable of being inverted and maintained in an inverted position to facilitate cleaning.

15 The invention consists in the construction and novel combination and arrangement of parts hereinafter fully described, illustrated 20 in the accompanying drawings, and pointed out in the claim hereto appended.

25 In the drawings, Figure 1 is a perspective view of a feed-trough constructed in accordance with this invention, the feed-receptacle being in an upright position. Fig. 2 is a transverse sectional view of the same. Fig. 3 is a similar view, the trough or receptacle being inverted. Fig. 4 is a detail perspective view of the fastening device.

30 Like numerals of reference designate corresponding parts in all the figures of the drawings.

35 1 designates a supporting-frame, comprising ends or standards 2 and top and bottom connecting-bars 3 and 4, secured to the ends or standards, which are provided between their ends with bearings 5, receiving the pin-tles or trunnions 6 of a pivoted trough or receptacle 7. The trough or receptacle 7, which 40 has its ends pivoted to the ends of the supporting-frame, is adapted to be inverted to the position shown in Fig. 3 of the accompanying drawings to discharge any of its contents and to facilitate cleaning, and it is prefer- 45 ably divided into separate compartments 8 by suitable transverse and longitudinal partitions; but the construction of the trough or receptacle may be varied, as will be readily understood.

50 In order to retain the feed-trough in an up-

right position to prevent it from being accidentally overturned by stock, a locking device 9 is provided, which locking device is also capable of maintaining the trough in an inverted position. The locking device comprises a hasp 10 and a swinging hook 11. The hasp is hinged at its upper end to one end of the frame by a staple 12 or other suitable fastening device, and its lower end is provided with a slot 13, adapted for the reception of staples or eyes 14 and 15, located at opposite sides of the trough and arranged, respectively, to engage the hasp when the trough is in an upright and in an inverted position. The staple 14 is arranged at the upper edges of the trough, and the staple 15, which is arranged at the opposite side of the same, is located between the top and bottom of the trough, as clearly shown in Figs. 2 and 3. The staple projecting through the hasp 70 is engaged by the swinging hook, which is pivoted or hinged to the outer face of the hasp, with its engaging portion or bill extending transversely of the slot, and it is adapted to be readily engaged with and disengaged from 75 either eye or staple of the trough, as will be readily seen. The upper end of the hasp is bent upon itself to form an eye for the reception of the pintle or fastening device 12, and the turned-over or inwardly-bent portion 16 80 is provided with a perforation, through which the upper end of the shank of the hook is passed, whereby the hook is hinged or pivoted to the hasp. The shank of the hook after being passed through the perforation of the 85 portion 16 of the hasp is bent down upon the same; but instead of pivoting the hook in this manner other means may be employed.

The invention has the following advantages: The feed-trough is simple and comparatively inexpensive in construction, and it is adapted to be inverted to discharge any of its contents and to facilitate cleaning. The fastening device, which holds the trough or receptacle in an upright position to prevent 90 it from being accidentally upset by stock, is also capable of maintaining the trough in an inverted position.

Changes in the form, proportion, and minor details of construction within the scope of the 100

appended claim may be resorted to without departing from the spirit or sacrificing any of the advantages of this invention.

What is claimed is—

- 5 The supporting-frame, combined with the trough pivotally mounted thereon, the staple 12 secured to the frame, and the staples 14 and 15 secured to the trough, the hasp having its upper end bent upon itself to form an
- 10 eye which is engaged with the staple 12, and an extended portion provided with an opening, and a hook 11 having the upper end of

its shank engaged in the said opening, the outer or lower end of the hook coöperating with the same end of the hasp to lock the latter to either of the staples 14,15, substantially as described.

In testimony that I claim the foregoing as my own I have hereto affixed my signature in the presence of two witnesses.

WAYNE ZONKER.
